UNITED STATES PATENT OFFICE.

LOUIS V. ARONSON, OF NEWARK, NEW JERSEY.

DESIGN FOR A KAZOO.

56,114.

Specification for Design.

Patented Aug. 24, 1920.

Application filed September 25, 1919. Serial No. 326,403. Term of patent 3½ years.

To all whom it may concern:

Be it known that I, LOUIS V. ARONSON, a citizen of the United States, residing in the city of Newark, in the county of Essex and State of New Jersey, have invented a new, original, and ornamental Design for a Kazoo, of which the following is a specification, reference being had to the accompanying drawings, forming a part thereof,

In the drawings,

Figure 1 represents a front elevation of a kazoo, illustrating my new design.

Fig. 2 represents a side elevation of the same; and

Fig. 3 represents an elevation of the same.

I claim:

The ornamental design for a kazoo, as shown.

LOUIS V. ARONSON.

Witnesses:

ALEXANDER HAMS,

FRED'K C. FISCHER.
